SHOE

Philip W. Lown, Lewiston, Maine, assignor to Penobscot Shoe Co., Old Town, Maine, a corporation of Maine

Application July 21, 1950, Serial No. 11,282

Term of patent 7 years

(Cl. D7—6)

To all whom it may concern:

Be it known that I, Philip W. Lown, a citizen of the United States, residing at Lewiston, in the county of Androscoggin and State of Maine, have invented a new, original, and ornamental Design for a Shoe, of which the following is a specification, reference being had to the accompanying drawing, forming part thereof.

In the drawing

Fig. 1 is a top plan view slightly tilted forwardly, of a shoe, showing my new design;

Fig. 2 is a side elevational view thereof, showing my new design; and

Fig. 3 is a front perspective view thereof, showing my new design.

The dominant features of my design reside in the portions shown in full lines.

I claim:

The ornamental design for a shoe, substantially as shown and described.

PHILIP W. LOWN.
